LAVATORY OR THE LIKE

Pietro M. Audino, Woodcliff Lake, N.J., and Lewis L. Bognar, Painted Post, and Humphrey Chang, New York, N.Y., assignors to Corning Glass Works, Corning, N.Y., a corporation of New York

Filed June 23, 1969, Ser. No. 17,825

Term of patent 14 years

Int. Cl. D23—02

U.S. Cl. D23—58

Fig. 1

Fig. 2

Fig. 3

Fig. 4

Fig. 5

Fig. 6

FIG. 1 is a top plan view of a lavatory or the like embodying our new design, portions of the counter top being broken away to indicate indefinite length.

FIG. 2 is a fragmental cross sectional view taken on line 2—2 of FIG. 1.

FIG. 3 is a fragmental cross sectional view taken on line 3—3 of FIG. 1.

FIG. 4 is a front elevational view thereof.

FIG. 5 is a bottom plan view thereof.

FIG. 6 is a fragmental cross sectional view taken on line 6—6 of FIG. 1.

We claim:

The ornamental design for a lavatory or the like, as shown.
